BALING-PRESS-RETAINER LOCK.

1,149,243.

Specification of Letters Patent. Patented Aug. 10, 1915.

Application filed February 24, 1915. Serial No. 10,287.

To all whom it may concern:

Be it known that I, LAURENCE C. YOUNG, a citizen of the United States, residing at Montgomery, in the county of Montgomery and State of Alabama, have invented certain new and useful Improvements in Baling-Press-Retainer Locks, and do hereby declare the following to be a full, clear, and exact description of the invention, such as 10 will enable others skilled in the art to which it appertains to make and use the same.

The primary object in view is the maintenance of the retainers in operative position while the press is receiving cotton from the 15 gins, and the automatic withdrawal of the retainers under compression.

With this and further objects in view, as will in part hereinafter be stated and in part become apparent, the invention comprises certain novel constructions, combinations of parts as will be hereinafter specified and claimed.

In the accompanying drawing,—Figure 1 is a fragmentary view in side elevation of a 25 baling press embodying the features of the present invention. Fig. 2 is an end view thereof.

It is to be understood that the invention is applicable to any of the common types of 30 presses, and for convenience has been illustrated as applied to a double box press consisting of boxes 1 and 2 mounted to revolve on the center post 14 so that cotton may be supplied to one of the boxes from the gins 35 while the cotton in the other box is being compressed. Fixed to each side of each of the boxes are journal bearing brackets 3 in the outer or bearing portions of which are journaled the shafts 5, one shaft being provided 40 at each side of each box, and each shaft 5 being formed with bent or crank-like portions 5' pivotally engaging the retainers 4 at the angle. Each retainer 4 consists of a right angle bar having a horizontal 45 arm extending through a slot in the respective side of the press box, and a vertical arm pendent from the horizontal arm, the bar being pivoted to the respective crank 5' at the angle so as to be free to move into and 50 out of operative position with the horizontal arm extending into the box accompanied by a compensatory movement of the respective crank 5'. The pendent arm of each retainer is provided with a bearing plate 4' at 55 its lower end portion and an enlargement or

weight 4" at such lower end portion for allowing the horizontal arm to swing vertically downward and to return to its horizontal position during the course of filling the box with cotton from the gins. To facilitate the passage of such cotton across the inner end of the horizontal arm of each retainer, the end is rounded at 4", the under edge of the arm being flat and straight so that while the cotton may pass freely from above down past the retainer it cannot expand upward past the same.

Each shaft 5 has one end portion bent substantially at right angles to the axis of the major portion of the shaft to form a docking arm 5² which terminates in a hook 5^a. A rock shaft 6 extends across each of the press boxes at that end adjacent the arm 5² and is journaled in appropriate bearings 6' carried by the respective box. Cotter pins 6^b extend through the shaft at the opposite ends of each bearing and engage the bearing for preventing axial reciprocation of the shaft. Each end portion of shaft 6 is bent to extend along the respective side of the box and is formed with a right-angle extension 6" disposed to engage the terminal portion of hook 5^a of the respective arm 5² for locking the shafts 5 against oscillation. Approximately midway of the length of shaft 6, a radial arm 6^a is fixed to the shaft and extends normally away from the respective press box a distance sufficient to, in operation, engage a cam block 8 which is carried by the strain rods 10 of the press, the block 8 being retained in position in any appropriate manner as by being clamped to the rods by the use of bolts connecting the block to a coöperating block or bar 9, or block 8 may be fixed in any suitable manner. The block 8 is formed with an incline or cam portion leading from each end, the incline in each instance starting below the lowest plane which the arm 6^a ever occupies so as to insure actuating the arm 6^a whenever either of the press containers or boxes is swung to position for receiving the thrust of the compression plunger. To insure maintenance of the respective arm 6^a against moving below the plane indicated, each press box carries a bracket 11 on which the arm 6 rests when not engaging the cam block 8.

When it is desired to retain shafts 5 of either box released for any given period, the respective arm 6^a is swung to the dotted line 110

position indicated on box 1 in Fig. 1, the upper end of the arm being sprung into locking engagement with a spring clip 12 for being thus retained until it again becomes desirable to employ the automatically releasing retainer lock.

The operation should be obvious and will be briefly stated as follows: The parts being in the position indicated in Fig. 1, cotton 10 is supplied from the gins to box 2 as usual up to the amount requisite for a bale. As the cotton passes the horizontal arms of the retainers, the retainers swing pivotally but the arms are held against withdrawing by the retention of rod 5 locked in its given position. When the requisite supply of cotton is complete, the boxes are swung on post 14 to the reverse position from that shown in the drawings, and in arriving in this position the retainer lock is released by the engagement of the respective arm 6^a with cam block 8 so that the parts assume the position indicated on box 1 in Fig. 1. The shaft 5 is thus released, and when the compression plunger ascends the retainers are free to move outward incident to the compensatory swinging of the cranks 5' until the parts arrive in the position indicated at the left hand side of Fig. 2. Thus the retainers automatically free themselves from danger and are not liable to be broken as often happens with retainers in present use which require either manual release or manual withdrawal. After the bale has been 35 "tied out" the box from which the bale has just been removed is swung around again to the filling position, and it is then necessary to manually restore the retainers to their operative position.

40 What I claim is:—

1. In a baling press, the combination, with a box, of retainers therefor movably mounted and adapted to extend into and to be retracted from the box, means for locking the retainers against retraction from the box, and means for automatically releasing said locking means.

2. In a baling press, the combination with a press box movable from a filling to a compression position, retainers movable into operative and inoperative position, means for locking the retainers in operative position against the pressure of the compressed material, and means for releasing the locking means to permit the retainers to be moved to inoperative position by the pressure of the compressed material.

3. In a baling press, the combination, with

a movably mounted box, adapted to be moved from filling position to a compression position, a retainer disposed to engage material in the box during the filling, means carrying the retainer adapted to be moved for shifting the retainer from the engaging to a non-engaging position, means for locking the retainer carrying means against movement, an operating arm for the locking means, and a cam disposed in the path of the operating arm for engaging and actuating the same for releasing the locking means when the box is moved to the compressing position.

4. In a baling press, the combination, with a movably mounted box adapted to be moved from a filling position to a compression position, retainers disposed to operate on material being filled into the box, means for locking the retainers in the operating position, a lock releasing arm adapted to release the retainers when the arm is actuated, and a cam disposed in the path of the arm for actuating the same as the box is being moved into the compression position.

5. In a baling press, the combination with a press box movable from a filling to a compression position, retainers located on each side of the press box, movable into operative and inoperative position, locking means for locking the retainers on each side of the press box in operative position, and means for automatically releasing the locking means for both sets of retainers simultaneously.

6. In a baling press, the combination with a press box movable from filling to compression position, retainers located at each side of the press box, movable into operative and inoperative position, and a single locking means for locking both sets of retainers in inoperative position, and means for releasing said locking means.

7. In a baling press, the combination with a movably mounted box adapted to be moved from a filling to a compression position, retainers disposed on both sides of the box to operate on material being filled into the box, a single locking arm for locking the retainers in operative position on both sides of the box, and means for automatically operating the arm to simultaneously release the retainers on both sides of the box.

LAURENCE C. YOUNG.
